(57) **CLAIM**

The ornamental design for a stand for a mobile device, as shown and described.

DESCRIPTION

FIG. 1 is a perspective view of my new design.

FIG. 2 is a front view of my new design.

FIG. 3 is a rear view of my new design.

FIG. 4 is a right side view of my new design.

FIG. 5 is a left side view of my new design.

FIG. 6 is a top view of my new design; and,

FIG. 7 is a bottom view of my new design.

Any shading lines are not features of the design but are utilized to illustrate surface contours of the stand in the drawings.

The novel design is for a stand used to display a mobile device.
